(57) **CLAIM**

The ornamental design for a display screen or portion thereof with a graphical user interface for an integrated disease management system, as shown and described.

DESCRIPTION

FIG. 1 is a front view of the display screen or portion thereof with a graphical user interface for an integrated disease management system in accordance with the present invention.

FIG. 2 is a back view of the display screen or portion thereof with a graphical user interface for an integrated disease management system of FIG. 1.

FIG. 3 is a first side view of the display screen or portion thereof with a graphical user interface for an integrated disease management system of FIG. 1.

FIG. 4 is a second side view of the display screen or portion thereof with a graphical user interface for an integrated disease management system of FIG. 1.

FIG. 5 is a top view of the display screen or portion thereof with a graphical user interface for an integrated disease management system of FIG. 1; and,

FIG. 6 is a bottom view of the display screen or portion thereof with a graphical user interface for an integrated disease management system of FIG. 1.

The outermost broken lines showing the display screen or portion thereof forms no part of the claimed design. The other broken lines in the figures show portions of graphical user interface that form no part of the claimed design.

1 Claim, 4 Drawing Sheets
